UNITED STATES PATENT OFFICE.

CHARLES FAYER, OF NEW YORK, N. Y., ASSIGNOR TO WAPPLER ELECTRIC COMPANY, INC., A CORPORATION OF NEW YORK.

TIME-CONTROLLED ELECTRIC SWITCH.

1,209,273.

Specification of Letters Patent. Patented Dec. 19, 1916.

Application filed June 12, 1916. Serial No. 103,132.

To all whom it may concern:

Be it known that I, CHARLES FAYER, a citizen of the United States, residing in the city of New York, borough of Bronx, in the 5 county of Bronx and State of New York, have invented new and useful Improvements in Time-Controlled Electric Switches, of which the following is a full, clear, and exact description.

0 My invention relates to time-controlled electric switches, of a kind suitable for timing the action of X-ray tubes and the like, exemplified for instance in the mechanism disclosed in Figures 1 to 6 inclusive 15 of my Patent No. 1,100,063 dated June 16, 1914.

In order to facilitate an understanding of my invention, I will first refer briefly to the structure and action of this general type 20 of switch as heretofore used in this art.

Contact mechanism is provided for opening and closing the circuit to be controlled. Closely associated with this contact mechanism, for the purpose of actuating it, is a 25 rocking lever which is movable in one direction by a pull cord operated by hand, and is movable in the opposite direction by pressure of a spring. The movement of the rocking lever in the direction first mentioned has no effect upon the circuit, which is normally open, but the single retrograde movement of the rocking lever, under pressure of the spring, so actuates the contact mechanism as to cause first the closing of 30 the circuit and then the opening thereof, the time interval between the closing and opening being the period during which the circuit is rendered active—say, for the excitation of an X-ray tube.

40 Connected with the rocking lever is a suction bellows provided with an air induct, and so arranged that the aforesaid movement of the lever by the pull cord causes the deflation of the bellows, and the retrograde movement of the lever, under pressure of the spring, causes the bellows to become inflated by the entrance of air through the induct. The operator, by adjusting the effective size of the induct, can regulate the 45 degree of retardation of the lever during 50

its retrograde movement, and by so doing can control the time during which the circuit remains closed. The bellows is provided with a venting valve for admitting air abruptly into the bellows in order to 55 enable the rocking lever to be shifted quickly under action of the pull cord. This venting valve, in the mechanism heretofore used, is very slow in its action.

By my present invention I seek to increase the efficiency of the switch, and particularly to accomplish the following results: I. To add a lever, conveniently designated as a setting lever and controllable by a pull cord, for the conjoint purpose of 60 shifting and setting the rocking lever in order to cause deflation of the bellows; preventing accidental engagement between the contact members during the shifting and setting of the rocking lever; and positively 65 holding open the venting valve of the bellows while the bellows is being deflated, thus insuring quickness of deflation. II. To add a trigger device, for the purpose of securing the rocking lever in the position into which 70 it is moved by the setting lever, the trigger device being controllable by a pull cord actuated by hand for causing the trigger device to release the rocking lever. III. To establish a connection from the setting lever 75 to the venting valve of the bellows, and so arrange the parts that when the setting lever is moved in order to set the rocking lever and deflate the bellows the venting valve is opened positively and held open until the 80 deflation of the bellows is completed and the rocking lever set. IV. To refine the adjustment of the air inlet and thus enable the operator to control more accurately the time 85 period during which the circuit is maintained closed by the contact mechanism.

Reference is to be made to the accompanying drawings forming a part of this specification, in which like letters indicate like parts in all of the views.

Fig. 1 is a plan view of my improved switch complete, the device being idle and the various movable parts occupying their normal positions. Fig. 2 is a detail view showing the movable wall of the bellows 95 100

partly broken away and the venting valve carried by said wall. Fig. 3 is a fragmentary plan of the contact mechanism the contact members being here shown in engagement with each other. Fig. 4 is a fragmentary plan of the device, showing the rocking lever as set, and various other movable parts occupying positions accordingly. Fig. 5 is a side elevation of the switch complete, the 10 rocking lever being set and other movable parts occupying positions accordingly. Fig. 6 is a section on the line 6—6 of Fig. 1, looking in the direction of the arrow, and showing the air inlet and means for adjusting 15 the same. Fig. 7 is a section on the line 7—7 of Fig. 1, looking in the direction of the arrows. Fig. 8 is a section on the line 8—8 of Fig. 1, looking in the direction of the arrows. 20 Secured rigidly upon a base 9 by fastenings 10 is a bracket 11, and carried by this bracket is a spider bar 12, held in position by screws 13. Adjacent this bar the bracket 11 is provided with a flat portion 14. A bellows 15 is provided with a fixed board 16 and with a movable board 17, the fixed board being secured rigidly to the bracket 11 by screws 11^a and pressing flush against the flat portion 14 thereof. A revoluble stem 30 18, carrying a handle 19, extends through the spider bar 12 and flat portion 14 and is thus journaled to these parts, as may be understood from Fig. 8.

Extending through the fixed board 16 is a hole 20, having a form nearly but not quite cylindrical, as it merges into a V-shaped channel 21. This hole serves as an air induct for the bellows. A snail cam 22 is mounted upon the stem 18 and revoluble therewith. 35 The cam is provided with a sleeve 23 integral with it and encircling the stem 18, upon which it is secured by a pin 24. The stem 18 carries a collar 25 secured rigidly upon it, and a spiral spring 26 lodged against 40 this cam, presses constantly against the snail cam so as to maintain a substantially airtight fit between the cam and the adjacent flat portion 14 of the bracket 11. The cam 22 carries a lug 22^a and the spider bar 12 is 45 provided with a lug 22^b against which the lug 22^a is adapted to lodge when the stem 18 is turned sufficiently in either of two directions. The lugs 22^a, 22^b thus constitute a 50 limiting stop for the rotary movement of the cam. The stem 18 is further provided with a collar 27, held in position upon it, by a screw 24^a, this collar having a finger 28 integral with it and serving as a pointer. The spider bar 12 has a flat, circular portion 29 55 upon which are marked graduations 30, the pointer and graduations together forming an indicator. As the stem 18 is rotated by hand the snail cam covers or uncovers the air inlet above described, and thus controls

the admission of air into the bellows. The 65 board 16 is further provided with a hole 31 of small size extending through it, and in registry with this hole is an adjusting screw 32. By adjusting this screw the hole 31 may be entirely or partially closed, as desired. 70 This hole 31, under control of the adjusting screw, serves to admit air into the bellows and thus serves as an auxiliary air inlet. It may be used or not, as desired, and if used may qualify the action of the main air in- 75 duct, consisting of the snail cam 22 and the air hole controlled thereby as above de- 80 scribed.

The movable board 17 of the bellows is 85 provided with a tubular sleeve 33 extending through it and held in place by screws 34. This sleeve serves as a vent, and is normally closed by a valve 35, which is carried by a lever 36, the latter having a fulcrum pin 37, mounted in bearings 38 so as to enable the 90 lever to rock. A compression spring 39 en- 95 gages the lever, and extends into a spring cup 40 carried by the movable board 17. The valve 35 is for the purpose of venting the bellows in order to facilitate the quick de- 100 flation thereof. A cord 41 is connected to the lever 37 and is used for actuating the same in order to displace the valve 35 and thus vent the bellows.

A connecting rod 42 is pivotally connected with the movable board 17 and also with a rocking lever 43, the latter being secured rigidly upon a short shaft 44. A spiral spring 45 encircles the shaft 44 and is provided with a straight portion of wire 46 100 which engages and presses constantly against a lug 47 carried by the rocking lever. The spring 45 is further provided with a straight portion of wire 48 which engages a stop pin 49, the latter being carried by a 105 tension disk 50. The tension disk is turned by hand in order to adjust the tension of the spiral spring, and is normally stationary, being locked in position by a nut 51, which is mounted upon a stem 52 to which the ten- 110 sion disk is rigidly secured. The stem 52 extends loosely through a bridge strap 53, which is secured by screws 54 to a spider bracket 55, the latter being also held rigidly upon the base 9 by the screws 54. The 115 spider bracket 55 is provided with two stop lugs 57, 58 for limiting the travel of the rocking lever 43, the lug 58 also co-acting 120 with the contact mechanism for the purpose of opening the circuit, as hereinafter de- 125 scribed. A contact bar 59 is provided with a contact member 60 and is supported by aid of a pair of lugs 61 which are integral with the rocking lever 43. The contact bar is thus fixed upon and carried by the rock- 125 ing lever, from which it is insulated by sleeves 62 of hard rubber or other appropriate insulating material. An insulated

conductor 63, such as a wire or cable, is connected to the contact bar 59.

The rocking lever 43 carries a pin 64, and journaled upon this pin is a contact lever 65, having a laterally extending arm 66 and therewith having the general form of a bell-crank lever. A tensile spring 67 extends from the arm 66 to a lug 68 which extends laterally from the rocking lever and is integral therewith. The contact lever 65 carries a contact member 69 which has a tendency to engage the contact member 58 above described. That is to say, the spring 67, being always under tension, tends to turn the contact lever 65 slightly in a clockwise direction according to Fig. 1, upon the pin 64 as a center, so as to bring the contact member 69 into engagement with the contact member 58. A guide 70, held in position by a screw 71, is provided for the contact lever 65, thus insuring correct registry between the contact members 69, 60, and also serving as a limiting stop for the contact lever 65 in one direction of its travel relatively to the rocking lever 43, as may be understood by comparing Figs. 1 and 3.

As the rocking lever 43, under pressure of the spring 45 (see Fig. 5) tends to turn in a clockwise direction according to Fig. 1, the outer or free end of the contact lever 65 tends to lodge against the lug 58, but the rocking lever 63 moves a little farther in the same direction of travel, that is, until the contact member 60 is drawn out of engagement with the contact member 69 and the guide 70, acting as a limiting stop, presses squarely against the adjacent edge of the contact lever 65. Thus, under normal conditions of idleness, the circuit controllable by the contact mechanism is open.

A setting lever 72 is journaled upon a post 73. Encircling this post is a spiral spring 74, the tendency of which is to turn the lever 72 in a clockwise direction according to Fig. 1. In this figure the lever is shown as occupying its normal position. The lever carries a lug 75, which lodges against a massive portion 76 of the bracket 55. It also carries a screw 77, to which the cord 41 is secured. The end portion 78 of the lever has an arcuate form. Adjacent this end portion is a pin 79, carried by the arm 66, and extending therefrom across the path of travel of the end portion. A pull cord 80 is secured to the outer end of the lever 72, and is used for turning or rocking the same in a contra-clockwise direction according to Fig. 1. A trigger 81, having the form of a latch, is provided with a notch 82 and is journaled to rock upon a pin 83. A spiral spring 84 presses upwardly against this trigger. A bolt 85 carries an eye 86, and secured to this eye is a pull cord 87 for actuating the trigger. An insulated con-

ductor 88 such as a wire or cable is connected to a binding post 89 upon the bracket 55.

Whenever the pull cord 80 is pulled by hand the setting lever 72 is turned a contra-clockwise direction according to Fig. 1; the cord 41 is thus drawn taut, and caused to pull the valve 35 away from its seat and thus vent the bellows. At the same instant the end portion 78 of the setting lever 72 engages the pin 79 and thus, by pulling upon the arm 66, prevents the contact member 69 from engaging the contact member 60, and also causes the lever 43 to rock in a contra-clockwise direction according to Fig. 1. Therefore, the trigger 81 is engaged by the adjacent free end of the bell-crank lever 65, which slips into the notch 82 (see Figs. 4 and 5), so that the trigger holds the bell-crank lever, and through it holds the rocking lever 43. The shifting and setting of the rocking lever 43, as just described, causes the connecting rod 42 to move to the left according to Fig. 1, so as to cause the bellows to be deflated or collapsed, this step taking place simultaneously with the venting of the bellows, by positive movement of the valve 35, as above described. The rocking lever thus being set and various other movable parts shifted accordingly, the cord 80 is now relaxed and the setting lever 72 returns to its normal position as shown in Fig. 4. The consequent relaxation of the cord 41 allows the valve 35 to close. This done, the apparatus can remain for any desired length of time without any change in its condition. Suppose, next, that the cord 87 is pulled by the operator. This rocks the latch 81, or in other words pulls the trigger, and liberates the bell-crank lever 65 and through it the rocking lever 43. Under impulse of the spring 67 the bell-crank lever 65 rocks upon the pin 64, so that the contact member 69 engages the contact member 60; and the rocking lever 43, under pressure of its spring 45 (see Fig. 5) turns in a clockwise direction according to Fig. 1. This movement of the rocking lever — its retrograde movement after being set and released — is comparatively slow, its speed being retarded by the bellows. The degree of speed permitted by the bellows is dependent upon the rapidity with which the bellows can become inflated by the entrance of air through the main and auxiliary air inducts. As the operator can control the admission of air through these inducts as above set forth, he can render the retrograde movement of the rocking lever slow or rapid, as he may desire.

Just before the rocking lever finishes its retrograde stroke the bell-crank lever lodges against the lug 58 and stops, so that as the rocking lever finishes its stroke the contact

member 60 is moved out of engagement with the contact member 69.

The operation of my device is as follows: The various parts being assembled and arranged as above described, I will suppose that at the start the apparatus is in its normal condition of idleness, as indicated in Figs. 1 and 5, and that the conductors 63 and 88 are in circuit with an X-ray tube and source of high-potential current for energizing the same—the circuit being open because the contact members 60, 69 are now disengaged.

The operator first assures himself that the polarity of the circuit is proper for that of the X-ray tube. Next he "times" the apparatus for the proposed exposure. To do this he turns the handle 19 and thus rotates the stem 18 and snail cam 22, so as to adjust the size, or air admitting capacity, of the hole 20 as above described. This will adjust the rapidity of movement of the bellows and all movable parts controllable thereby, during the retrograde movement of the rocking lever. That is, this adjustment will determine the time during which the rocking lever, if set and released, will make its retrograde movement, and consequently the time during which the circuit will remain closed. The time period thus determined is indicated by the position of the pointer 28 relatively to the graduations 30, as may be understood from Fig. 7. Any number of exposures may be made in succession with one determination of the time period. The operator next grasps the pull cord 80 and pulls it. This actuates the setting lever 72 as above described, and the setting lever pulls the cord 41, thus venting the bellows, and also sets the rocking lever without closing the contact mechanism. The rocking lever, acting through the connecting rod 42, deflates the bellows quickly, the venting of the bellows facilitating this purpose. The operator hears the click of the trigger 81 as the outer end of the lever 65 slips into the notch 82 (see Fig. 5) and is thus apprised when the rocking lever is completely set. He thereupon relaxes the pull cord 80 and removes his hand therefrom. This leaves the apparatus in the condition indicated in Fig. 4.

When the precise moment arrives for the exposure to be made, he merely grasps and tightens the pull cord 87. This causes the trigger to disengage the bell-crank lever 65, and in so doing to release the rocking lever 43. The result is that the bell-crank lever 65, acting under control of the spring 67, rocks slightly upon the pin 64 as a center, in a clockwise direction according to Fig. 4, and thus brings the contact member 69 into engagement with the contact member 60. The rocking lever 43, now being under

control of the spring 45, makes a general 65 retrograde movement, that is, rocks in a clockwise direction according to Fig. 4, at a rate of speed dependent upon the time interval previously selected. As the rocking lever 43 nears the limit of its travel the 70 outer or free end of the bell-crank lever 65 lodges against the stationary lug 58 and is thus brought to a stop, so that the farther movement of the lever 43 carries the contact member 60 out of engagement with the contact member 69. Then the lever 43 is brought to a standstill because the guide 60, acting as a limiting stop, lodges against the adjacent portion of the bell-crank lever. Thus at the finish of the exposure, the apparatus is left in its normal condition, shown in Fig. 1.

It will be noted that while the rocking lever is being shifted and set, by action of the setting lever, the setting lever positively 85 prevents the accidental engagement of the contact members, and also positively vents the bellows. The danger of accidental or premature closure of the circuit is thus prevented, the setting is accomplished with a 90 minimum of delay, and after the setting is completed, the operator need not concern himself about the condition of this part of the apparatus until he is ready to make the exposure. Then in making the exposure he 95 simply pulls a cord one time, this being a most natural, simple and easily performed movement.

All of the various mechanical steps above described are performed in successive order and with precision due to positive movement, by first a simple pull by hand upon one cord, to place practically the entire apparatus in condition for an exposure, and then another simple pull upon another cord, to make the exposure and restore the apparatus as a whole to its normal condition of idleness.

I do not limit myself to the specific use above suggested for my device, as it may be employed in a number of different relations. Neither do I limit myself to the particular form shown, as variations may be made therein without departing from the spirit of my invention.

I claim:

1. In an apparatus of the character described the combination of contact mechanism for opening and closing an electric circuit, a movable member connected to said contact mechanism for the purpose of actuating the same, means for conferring upon said movable member a movement in one direction to cause said contact mechanism to close and open said electric circuit, a pneumatic retarding device connected to said movable member in order to retard the movement thereof in said direction, a setting

- lever for shifting said movable member in the opposite direction and preventing said contact mechanism from being closed while said movable member is thus being shifted, 5 and trigger mechanism for holding said movable member in the position into which it is thus shifted, said trigger mechanism being controllable at the will of the operator for releasing said movable member.
- 10 2. In an apparatus of the character described the combination of contact mechanism for opening and closing an electric circuit, a movable member connected to said contact mechanism in order to actuate the same, means for conferring upon said movable member a movement in one direction to cause said contact mechanism to close and open said electric circuit, a pneumatic retarding device connected to said movable member in order to retard the movement thereof in said direction, a setting lever for shifting said movable member in the opposite direction, and mechanism connected with said setting lever and said pneumatic device 25 and controllable by a movement of said setting lever for venting said pneumatic device while said setting lever is shifting said movable member.
3. In an apparatus of the character described the combination of contact mechanism for closing and opening an electric circuit, a movable member connected to said contact mechanism, means for conferring upon said movable member a movement in one direction to cause said contact mechanism to close and open said electric circuit, a pneumatic retarding device connected to said movable member in order to retard the movement thereof in said direction, a setting 30 lever controllable at the will of the operator for shifting said movable member in the opposite direction, trigger mechanism for holding said movable member when thus shifted, said trigger mechanism being controllable at 35 the will of the operator for releasing said movable member, and means for retracting said setting lever into a predetermined normal position independently of the position in which the rocking lever is set.
- 40 4. In an apparatus of the character described the combination of contact mechanism for closing and opening an electric circuit, a movable member connected to said contact mechanism, means for conferring upon said movable member a movement in one direction to cause said contact mechanism to close and open said electric circuit, means for retarding said movable member as it moves in said direction, mechanism controllable at the will of the operator for shifting said movable member in the opposite direction and trigger mechanism for holding said movable member when thus shifted, said trigger mechanism being controllable at 45 the will of the operator for releasing said movable member.
- 50 5. In an apparatus of the character described, the combination of contact mechanism for closing and opening an electric circuit, a movable member connected to said contact mechanism, means for shifting the position of said movable member in order to actuate said contact mechanism, a pneumatic retarding device connected with said movable member for retarding the travel thereof, said pneumatic retarding device having an air hole and a channel merging into said air hole for admitting air, said pneumatic device being further provided with a snail cam disposed adjacent said air hole and channel, and adjustable for the purpose of adjusting the capacity thereof.
- 55 6. In an apparatus of the character described the combination of contact mechanism for closing and opening an electric circuit, a movable member connected to said contact mechanism, means for shifting the position of said movable member in order to actuate said contact mechanism, a pneumatic retarding device connected with said movable member for retarding the travel thereof, said pneumatic retarding device having an air hole and a channel of substantially 60 V-form in cross section merging into said air hole, said pneumatic device being further provided with a flat snail cam disposed adjacent said air hole and channel for the purpose of partially obstructing the same, and with means for enabling the operator to turn said snail cam.
7. The combination of a rocking lever, contact mechanism carried by said rocking lever and controllable by movements thereof for closing and opening an electric circuit, a pneumatic retarding device connected with 65 said rocking lever for retarding the movement thereof in order to time the opening and closing of said circuit, said retarding device being provided with a vent adapted to be opened in order to prevent said retarding device from retarding the restoration of said rocking lever to a predetermined position, a setting lever movable at 70 the will of the operator for restoring said rocking lever to its said position, and means 75 controllable by said setting lever for opening said vent.
8. The combination of a rocking lever, contact mechanism carried by said rocking lever and controllable by a movement thereof in one direction for closing and opening an electric circuit, a retarding device connected with said rocking lever in order to retard said movement thereof and thus time the action of said contact mechanism, a setting lever disposed adjacent said rocking lever and controllable at the will of the operator for engaging said setting lever and 80

6 shifting the same into a predetermined position, and trigger mechanism for holding said rocking lever in said position, said trigger mechanism being controllable at the will of the operator for releasing said rocking lever.

9. A device of the character described, comprising a rocking lever, contact mechanism carried by said rocking lever and controllable by a movement thereof for the purpose of closing and opening an electric cir-

cuit, trigger mechanism disposed partially within the path of travel of said contact mechanism for the purpose of engaging said contact mechanism and temporarily preventing movement of said contact mechanism and of said rocking lever, and means controllable at the will of the operator for actuating said trigger mechanism in order to release said rocking lever. 15

CHARLES FAYER.
